CLAIM

The ornamental design for a feeding, teething, and/or entertaining device, as shown and described herein.

DESCRIPTION

FIG. 1 is an isometric view of a top, front, and right side of an ornamental design for a feeding, teething, and/or entertaining device;

FIG. 2 is an isometric view of a top, rear, and left side of the feeding, teething, and/or entertaining device of FIG. 1;

FIG. 3 is a front elevational view of the feeding, teething,

and/or entertaining device of FIG. 1; and,

FIG. 4 is a bottom elevational view of the feeding, teething,

and/or entertaining device of FIG. 1.

(Continued)

The broken lines, where present, in any FIGS. illustrate portions of the feeding, teething, and/or entertaining device that form no part of the claimed design.

1 Claim, 2 Drawing Sheets
